Patented Apr. 3, 1917.

UNITED STATES PATENT OFFICE.

GEORGE F. EARNSHAW, OF CHICAGO, ILLINOIS, ASSIGNOR TO EARNSHAW KNITTING CO., OF CHICAGO, ILLINOIS, A CORPORATION OF ILLINOIS.

CHILD'S SLEEPING-GARMENT.

1,221,710.

Specification of Letters Patent.

Patented Apr. 3, 1917.

Application filed June 9, 1915. Serial No. 33,034.

To all whom it may concern:

Be it known that I, GEORGE F. EARNSHAW, a citizen of the United States, residing at Chicago, in the county of Cook and State of Illinois, have invented certain new and useful Improvements in Children's Sleeping-Garments, of which the following is a specification.

This invention relates to improvements in sleeping garments of that type commonly worn by babies and small children, wherein the body and sleeves are of sufficient length to enable the ends to be drawn together and closed by drawstrings when the garment is worn. In such garments as heretofore made the sleeves have been attached to the body portion by seams extending between the shoulders and the arm pits, as usual in most sleeved garments. This latter construction, as embodied in a child's sleeping garment of the character mentioned has one serious objection, in that a drawing or pulling down action on the body of the garment, which frequently occurs owing to the restlessness of the child, especially where the garment is shorter than it should be, creates more or less of a downward pull on the shoulders of the child transmitted through the substantially non-elastic shoulder seams, thus tending to make the child round shouldered.

The object of my present invention is to produce a garment which shall entirely obviate the above mentioned objection, and this object I secure by uniting the sleeves to the body portion by oblique seams which extend between the neck and arm pits of the garment, leaving the shoulder portions integral with the arm portions. This construction transmits the strains caused by a downward pull on the body not to the shoulders but to the base of the neck, this portion of the child's body being much better able to withstand such strains without injury or deformity, due to the resistance of the backbone and the relatively strong neck and back muscles.

In the accompanying drawings I have illustrated a sleeping garment embodying my invention, and referring thereto—

50 Figure 1 is a front elevation of the garment with the sleeves extended substantially

at right angles to the median line of the body; and

Fig. 2 is a similar rear elevation of the garment.

55

Referring to the drawings, 5 designates the front portion, and 6 the rear portion of a child's garment, which may be assumed to be made of knit material; these portions being united by longitudinal side seams 7. At 60 the lower portion of the body portion is a hem or casing 8 in which is inserted the usual drawstring 9 for closing the lower end of the garment when the latter is on the child. 10 designates the sleeves, the outer 65 ends of which are formed with similar hems or casings 11 containing drawstrings 12 for closing the outer ends of the sleeves.

13 is the neck portion finished in the usual manner, and 14 (Fig. 2) designates the rear 70 opening closed by tie strings 15, as usual in garments of this type.

The sleeves 10, instead of being attached to the body portion by the usual seams running through the arm pits and over the 75 shoulders, are attached by oblique front and rear seams 16 and 17 that start from the neck 13 and are continuous through the arm pits.

It is well known that in all garments, even 80 knitted garments, the seams are substantially inelastic, having very little stretch. It will thus be seen that in the garment herein shown and described, especially when the same is made of knit material, practically none of the downward pull on the body is transmitted to the shoulder portions, but substantially all of this downward pull is transmitted through the oblique seams 16, 17 to the neck portions where, as above 90 stated, it can work practically no inconvenience or harm to the child.

I claim:

An article of the character described comprising an infant's sleeping garment of full 95 length, the same possessing a body portion having sleeves, a neck opening, and an open lower end provided with means for closing the same below the feet of the infant, said body part being formed in part of continuous elastic material extending over and around the shoulder portions to render the 100

latter seamless and relatively unrestrained throughout so as to give and prevent downward pulls incident to pressure of the feet of the infant against the closed end of the 5 garment from being transmitted to the shoulders of the infant, in combination with means for tying the garment about the neck

of the infant, and relatively inelastic oblique seams extending from the neck to approximately the arm pits for transmitting the 10 pulling strains to the neck portion of the garment as the elastic limit of the shoulder portions thereof is reached.

GEORGE F. EARNSHAW.
